UNITED STATES PATENT OFFICE.

STACY B. HASELTINE, OF CHICAGO, ILLINOIS, ASSIGNOR TO W. H. MINER, INC., OF CHICAGO, ILLINOIS, A CORPORATION OF DELAWARE.

REFRIGERATOR-DOOR-OPERATING MECHANISM.

Application filed November 16, 1925. Serial No. 69,221.

This invention relates to improvements in refrigerator car door operating mechanisms.

One object of the invention is to provide a simple and efficient arrangement of door operating mechanism, especially adapted for refrigerator car doors, for forcing the doors to tightly closed position, for holding the same closed, and which will also be effective in starting the door opening operation.

10 A more specific object of the invention is to provide a mechanism of the character indicated, especially designed for operating doors of the swinging type, including a rotary operating shaft having an off-set portion functioning as an operating crank arm, in conjunction with a transmitting element connected to said crank arm and having an actuating portion movably mounted on said door and confined to a path of movement substantially parallel with the plane of the face of the door, said actuating portion being adapted to co-act with a fixed keeper secured to the door frame.

25 Other objects and advantages of the invention will more clearly appear from the description and claims hereinafter following.

In the drawings forming a part of this specification, Figure 1 is a side elevational view of a portion of a refrigerator car, showing my improvements in connection therewith. Figure 2 is an enlarged, vertical, sectional view, partly broken away, corresponding substantially to the line 2-2 of Figure 1. Figure 3 is a horizontal, sectional view, corresponding substantially to the line 3-3 of Figure 1. Figure 4 is a horizontal, sectional view, corresponding substantially to the line 4-4 of Figure 2, through the actuating portion of the transmitting member, showing in detail the lower keeper, and illustrating the position of the actuating portion when the door is fully closed, and after the same has been forced open to clear the insulation. And Figure 5 is a fragmentary enlarged elevational view of the lower crank arm, bearing brackets, actuating member, and associated keeper, as shown in Figure 1.

50 In said drawing, the car is shown as provided with a door frame 10 and two pivoted doors 11 and 12 having meeting beveled edges in the usual manner. As is customary in refrigerator cars, insulation or packing is employed between the meeting edges of the door faces and around the sides and top.

The doors 11 and 12 are mounted to swing about vertical axes, being supported by suitable hinges 13.

55 As shown, the improved door operating mechanism comprises, broadly, an operating shaft A provided with two end castings B-B, and an operating handle C; upper and lower bearing brackets D-D; a pair of upper and lower actuating members E-E; and a pair of upper and lower keepers F-F. The operating shaft is preferably in the 60 form of a flat bar of rectangular cross-section, having the handle or lever C pivoted thereto by a pin 20.

65 The castings B are disposed respectively at the upper and lower ends of the shaft A. 70 Each of the end castings B-B, as shown, is preferably in the form of a crank having a cylindrical journal portion 21 alined with the axis of the operating shaft and an offset end portion or crank 22. Each casting B is 75 formed with a head 23 at the inner end of the journal portion 21, said head being vertically slotted as indicated at 24 to receive the corresponding end of the shaft A, to which it is fixed by rivets 25 or other suitable 80 securing means.

85 The bearing brackets D-D, which are of similar construction, are respectively mounted at the upper and lower edges of the door 12 adjacent the free forward edge thereof. 90 Each of the brackets D comprises a housing including a plate-like base portion 26, having formed on the outer face thereof adjacent the inner edge, a lug 27 having a concave bearing seat 28, for the reception of the 95 journal portion 21 of the member B. A strap 29 is provided which has a central looped portion 30 which co-operates with the concave bearing seat 28 to maintain the journal portion 21 in position, said strap 100 having oppositely disposed flanges 31 through which are passed suitable securing bolts 32, which bolts pass through the plate 26 and secure the parts together and to the door 12.

105 Formed on the outer end of the plate 26 of each bracket D, is a horizontally extending wall 33, which forms the bottom wall of a housing adapted for mounting the actuating member E. Said housing includes an outer vertically disposed wall 34, a rear wall 35, a top wall 36, and a forward wall 37, the top wall 36 preferably terminat-

ing a considerable distance from the forward wall 37, and the front wall 34 terminating a considerable distance from said forward wall, the front wall 34 and the front edge of the bottom wall 33 diverging outwardly to provide an increased space between the wall 26 and the front extremity of the bracket, as indicated at 38. The outermost wall 33 of the bracket is provided with 10 an elongated slot 39, which extends substantially parallel with the plane of the face of the door 12, the bottom wall 33 being provided with an upstanding flange 40 on its outer side bounding said slot. The actuating members E are two in number, and each comprises an elongated plate-like body member 41 having an actuating portion 42 slidably disposed in the slot 39 and extending through said slot and outwardly beyond 15 the adjacent edge of the door 12. The forward portion of the member 41 rests upon the wall 33, and is provided with an opening for the reception of the crank end 43, which is preferably of cylindrical cross- 20 section.

The upper and lower keepers F—F, which are mounted on the lintel and threshold of the door frame, are of substantially similar construction, each comprising a vertically disposed plate-like portion 44 by which the keeper is bolted to the car. Each keeper is provided with a slot 45, the defining walls of the inner portion 46 of which are disposed substantially parallel to the plane of the face of the door frame, and the walls of the remaining portion of said slot extending outwardly at an angle to the plane of the face of the car frame as indicated at 47, the slots 45 being adapted for the 25 reception of the actuating portion 42, of each actuating member E. The plate 44 of the lower keeper F is extended to the left, as seen in Figure 1, beyond the edge of the door 11, and has pivotally mounted thereon 30 a latch member 48 adapted to co-act with a plate 49 fixed to the door 11 adjacent the lower outer corner thereof. The latch 48 serves to retain the door 11 in position when closed and to prevent the doors from jamming in the door opening when opening the 35 right hand door. The handle C is adapted to be locked as shown in Figure 1, by any suitable locking device as indicated at 50, and sealed in any suitable manner customary 40 in connection with railway cars.

In operation, my improved mechanism works as follows, assuming the doors to be in closed position, and that it is desired to open the doors. With the doors closed, 55 movement of the lever C outwardly away from the door 11 will impart rotation to the shaft A and consequently to the crank portion 43 fixed thereto. Said crank portion due to its pivotal connection to the plate 60 member 41 will impart movement thereto

in a right hand direction, carrying therewith the actuating portion 42 on the plate, which is confined to movement parallel to the plane of the face of the door 12 by the walls of the slot 39, said actuating portion 70 engaging the cam walls of the slot 45 in the related keeper, thereby forcing the door outwardly until the actuating portions 42 may be retracted from the open ends of the slots, and the door swung to fully open position. 75 When it is desired to close the doors, the door 12 is swung inwardly until the actuating portions 42 are aligned with the open ends of the slots 45 in the keepers F, after which a movement of the lever C away from 80 the door 12, by reason of the corresponding movement of the crank, will cause travel of the actuating member D in a left hand direction, the actuating portion 42 traveling along the inclined face in the slot and serving to close the door, the portion 46 of the slot which is disposed substantially parallel to the plane of the face of the door frame, providing means which overcome the tendency of the actuating portion to move out 85 of the inclined slots.

By the above described arrangement, it will be appreciated that the arcuate movement of the cranks which furnish the power for operating the door mechanism is transformed or converted into movement substantially parallel with the face of the door in a simple and effective manner.

While I have herein shown and described what I now consider the preferred manner of carrying out my invention, the same is merely illustrative and I contemplate all changes and modifications that come within the scope of the claims appended hereto.

I claim:

1. In a door operating mechanism, the combination with a member providing a door opening and a pivoted door; of means for effecting opening and closing movements of said door, said means including a rotatable shaft having crank portions thereon; keeper means affixed to the door frame and having camming faces; means including an actuating portion adapted to co-act with the cam faces of said keeper means; and means for transmitting the movement of said crank means to said actuating portion, said means being arranged to convert the arcuate movement of said crank into rectilinear movement of said actuating portion.

2. In a door operating mechanism, the combination with a member providing a door opening and a pivoted door; of means for effecting opening and closing movements of said door, including an actuating element adapted to travel transversely of said door in a path substantially parallel with the plane of the face of said door; independent operating means held against travel with reference to said door and arranged to im-

part operative movements to said actuating element; and keeper means affixed to said door frame and having cam faces adapted to be engaged by said actuating portions.

5 3. In a door operating mechanism, the combination with a member providing a door opening and a pivoted door; of means for effecting opening and closing movements of said door, including keeper means mounted on said member; an actuating element slidably mounted on said door and arranged to move in a path substantially parallel to the plane of the face of said door, said actuating portion being adapted to co-operate 15 with said keeper means to effect opening and closing movements of said door; and means for imparting sliding movements to said actuating element.

4. In a refrigerator car having a pivoted side door, the combination with an operating shaft rotatably mounted on said door, said shaft being provided with offset crank portions; an elongated actuating member having one portion pivotally connected to said 25 crank means and an actuating portion pivotally and slidably mounted on said door, said actuating portion extending outwardly beyond the edge of said door; and keeper means connected to the car and adapted to 30 co-operate with said actuating portions to effect opening and closing movements of said door.

5. In a refrigerator car having a pivoted side door, the combination with brackets secured to said door adjacent the top and bottom edges thereof, each of said brackets being provided with a supporting wall extending substantially horizontally outwardly from the face of said door, each of said walls 40 being provided with a slot arranged substantially parallel with the face of the door; actuating members having actuating portions pivotally and slidably mounted in said slots, and body portions bearing against said 45 supporting walls; a shaft rotatably mounted in said brackets, said shaft being provided with offset crank portions pivotally connected to the body portions of said actuating members; and keeper means connected 50 to said car and co-operating with said actuating portions to effect movements of said door.

6. In a refrigerator car, the combination with a pivoted side door; of a shaft rotatably mounted on said door and having offset crank portions thereon; actuating members having actuating portions confined to movements substantially parallel with the plane of the face of said door, said actuating portions being connected to said crank means and movable thereby, and keepers affixed to the door frame and cooperating with said actuating portions, said keepers having cam surfaces, the outer portions of 60 which extend at an angle to the face of the

door frame, and the inner portions of which extend substantially parallel to the face of said frame.

7. In a door opening device, in combination with a door and a surrounding casing, a rock shaft rotatably mounted on one of said structures, a cam track on the other of said structures, a guideway in co-acting relation to said track and mounted on the structure which carries the shaft, a movable cross connection operating jointly within said cam and said trackway, and means actuated by the shaft for imparting movements to said cross connection for causing the same to ride upon the cam track and impart an opening movement through the guideway to the door, substantially as described. 70 75 80

8. In a door opening device, in combination with a door and a surrounding casing, a rock shaft rotatably mounted on one of said structures, a cam track on the other of said structures, a guideway in co-acting relation to said track and mounted on the structure which carries the shaft, a movable cross connection operating jointly within said cam and said trackway, and means actuated by the shaft for imparting movements to said cross connection for causing the same to ride upon the cam track and impart an opening movement through the guideway to the door, a handle connected with said shaft, and a keeper for holding said handle locked in proximate relation to said door when the cross connection is retracted along the cam, substantially as described. 85 90 95 100

9. In a door opening device, in combination with a door and a surrounding casing, a rock shaft rotatably mounted on one of said structures, a crank on the end of the rock shaft, a cam track on the other of said structures, a guideway in co-acting relation to said track and mounted on the structure which carries the shaft, a movable cross connection operating jointly within said cam and said trackway, and means actuated by the shaft crank for imparting movements to said cross connection for causing the same to ride upon the cam track and impart an opening movement through the guideway to the door, substantially as described. 105 110 115

10. In a door opening device, in combination with a door and a surrounding casing, a rock shaft rotatably mounted on one of said structures, a crank on the end of the rock shaft, a cam track on the other of said structures, a guideway in co-acting relation to said track and mounted on the structure which carries the shaft, a movable cross connection operating jointly within said cam and said trackway, and means actuated by the shaft crank for imparting movements to said cross connection for causing the same to ride upon the cam track and impart an opening movement through the guideway to the 120 125 130

door, a handle connected with said shaft, and a keeper for holding said handle locked in proximate relation to said door when the cross connection is retracted along the cam, 5 substantially as described.

11. In a door opening device, in combination with a door and a surrounding door casing, a shaft rotatably mounted on the door, a handle for rotating the shaft, a guideway 10 mounted near one edge of the door, a cam track on the casing in proximate relation to the guideway when the door is closed, a

cross connection between the cam trackway and the guideway, a crank on the shaft, and a connection between said crank and said 15 cross connection for imparting travel to the latter, to cause the same to ride up on the cam trackway for opening the door substantially as described.

In witness that I claim the foregoing I 20 have hereunto subscribed my name this 13th day of November, 1925.

STACY B. HASELTINE.
